HENRY L. JESSEN, OF ALAMEDA, CALIFORNIA

OIL BURNER

Application filed April 13, 1927. Serial No. 183,604.

My invention is an improved oil burner, particularly applicable to cook stoves.

The object of my invention is to provide a burner which is simple in construction, and 5 inexpensive to manufacture.

My invention comprises an open faced oil gasifying plate mounted at an inclination and down which oil may trickle, the upper face of the plate being closed in by a conduit through 10 which air passes to the furnace. In starting the burner the oil is allowed to drip down the gasifying plate into a starting pan below the plate. The oil in this pan is ignited and in 15 burning heats the gasifying plate to such a temperature that the oil becomes gasified and is carried with the air passing downward in the conduit and burns beyond the mouth of the conduit. After this the heat of the furnace maintains the gasifying plate at sufficient 20 temperature to gasify the oil. Another object is to have a passage open at both ends over the gasifying plate so that the soot or any carbon which forms on the plate will be readily 25 cleaned off by inserting a suitable implement through the outer open end of the conduit.

Other novel features and advantages will be more specifically described in the following detailed description.

In the annexed drawing in which my invention is illustrated:

Figure 1 is a side view of my burner attached to a stove.

Figure 2 is a longitudinal sectional view of the burner.

Figure 3 is a sectional view taken on the line 3—3 of Figure 2.

Figure 4 is a plan view of the burner plate.

Figure 5 is a sectional view taken on the line 5—5 of Figure 4.

Referring more particularly to the drawing, a burner mounting plate 1 is suitably secured to the front of the stove 2. A conduit 3 is secured within the opening 4 in the plate 1, the top and bottom walls of which converge 45 towards the rear to form a mouth 5. The rear end of the conduit 3 is supported by a bracket 6 in the stove 2.

A burner plate 7 rests upon the lower wall of the conduit 3 and a lip 8 on said plate projects beyond the rear edge of the conduit, the

purpose of which will be further described. This plate slants downward and rearwardly to a point adjacent its inner end where it is carried rearwardly in substantial parallelism with the bottom of the stove for the purpose 55 of checking and bringing to rest the downward moving sheet of oil flowing over the plate so that the oil flows to the rear of the plate by gravity. The pipe 9 conducts oil to the forward end of the plate 7, and a distributor plate 10 spreads the oil over the entire surface of the plate. A plurality of grooves 11 in the bottom of the plate 10 permit the passage of oil therethrough. Riffle bars 12 are formed on the surface of the plate 7 which 60 retard the direct flow of the oil, and prevent it from flowing over the end of the said plate.

A drip plate or ignition pan 13 which slopes forwardly and downwardly to a point adjacent its forward end where it is carried forward in substantial parallelism with the bottom of the stove for the purpose of arresting the flow of oil which will be gasified and ignited thereon and further heat plate 7 for 65 the gasification of oil flowing thereover from pipe 9 is positioned under the plate 7 and is secured to the bracket 6. The operation of the plate will be further described.

The operation of my burner is as follows: Oil is fed through the pipe 9 by gravity and 70 drops upon the plate 7 in front of the distributor plate 10, which spreads the oil over the entire surface of the plate. The oil flows into the ignition pan 13 over the end of the plate 7, and is ignited on the said pan, which 75 heats the plate to the temperature at which the oil vaporizes. When the plate is heated to the vaporization temperature the oil vaporizes before it reaches the lip 8, and burns at the mouth 5. The velocity of the air over the plate 7 is determined by the size of the mouth 5. The size of the mouth 5 is determined by experiment, so that all of the oil vapor is carried through the mouth and burns above the lip 8.

It will be noted that the conduit 3 is made of thin metal and the plate 7, which may be designated as a gasifying plate, is comparatively thick, being preferably made of cast iron. When the oil in the pan 13 is ignited 100

the heat is readily conducted through the lower wall of the conduit 3, to the plate 7, heating the same and thereby gasifying the oil held thereon. The draft of air through the opening 4 and down the closed conduit 3, above the face of the plate, carries the gas generated from the oil through the mouth 5, whence it becomes ignited and continues to burn. In actual practice the flame starts well clear of the lip 8, so that very little soot or carbon is deposited on the plate or the lip. The heat of the furnace maintains the temperature of the plate 7 which continues to gasify the oil.

15 I claim:

1. The combination with a stove having an opening in the wall thereof, of an apertured supporting plate spanning the opening, an inwardly extending conduit supported at one 20 of its ends by the plate, a bracket within the stove for supporting the other of the ends of the conduit, a gasifying plate resting on the bottom of the conduit and bent at an angle adjacent its inner end, the portion of the 25 plate intermediate the inner end and the bend lying in parallelism with the bottom of the stove, an ignition pan supported by the bracket with its inner end extending beyond the inner end of the gasifying plate and ex- 30 tending forwardly and downwardly and bent at a point adjacent its outer end, the portion between the bend and the outer end lying in substantial parallelism with the bottom of the stove and means for conveying fuel oil 35 to the conduit.

2. The combination with a stove having an opening through one of its walls, a supporting plate having a portion offset from the wall of the stove, an inwardly and downwardly tapering conduit supported at its outer end by the supporting plate, a gasifying plate supported by the bottom wall of the conduit, said plate having its inner portion lying in parallelism with the bottom of the stove, a 40 combined drip and gasifying plate extending beyond the inner end of the first named gasifying plate and extending forwardly and downwardly with the forward portion thereof lying in substantial parallelism with the bottom of the stove, a bracket for supporting the gasifying plates in spaced relation, and an oil feed pipe extending through the first mentioned gasifying plate for delivering fuel oil thereto.

45 3. The combination with a stove having an opening through one of its walls, a supporting plate having a portion offset from the wall of the stove, an inwardly and downwardly tapering conduit supported at its outer end by the supporting plate, a gasifying plate supported by the bottom wall of the conduit, said plate having its inner portion lying in parallelism with the bottom of the stove, a combined drip and gasifying plate 50 extending beyond the inner end of the first

named gasifying plate and extending forwardly and downwardly with the forward portion thereof lying in substantial parallelism with the bottom of the stove, a bracket for supporting the gasifying plates in spaced relation, an oil feed pipe extending through the first mentioned gasifying plate for delivering fuel oil thereto, the first mentioned gasifying plate being provided with riffle bars, and an apertured distributor plate intermediate the fuel pipe and the riffle bars.

70 In testimony whereof I affix my signature.

75 HENRY L. JESSEN.
